(57) **ABSTRACT**

A new *Helleborus* plant particularly distinguished by abundant purple flowers, upright plant habit and a vigorous growth habit, is disclosed.

1 Drawing Sheet

1

Genus and species: *Helleborus*×*hybridus*.
Variety denomination: 'ABCRD02'.

BACKGROUND OF THE NEW PLANT

The present invention comprises a new and distinct variety botanically known as *Helleborus*×*hybridus*, and hereinafter referred to by the variety name 'ABCRD02'. The new variety originated from a controlled hybridization conducted in February 2005 in Devon, United Kingdom, between female hellebore plant *Helleborus* nr. 'RD369HK01' (unpatented) and male hellebore plant *Helleborus* nr. 'RD959NB97' (unpatented). The seeds produced by the hybridization were sown in Devon, United Kingdom. A single plant selection was chosen for further evaluation and for asexual propagation in Devon, United Kingdom.

'ABCRD02' was subsequently asexually propagated by tissue culture in Aalsmeer, The Netherlands for at least 3 years. The present invention has been found to retain its distinctive characteristics through successive asexual propagations for at least 30 generations.

Community Plant Variety Rights (CPVR) for this variety were applied for in Europe on Jan. 25, 2012. 'ABCRD02' has not been made publicly available more than one year prior to filing of this application.

SUMMARY OF THE INVENTION

The following are the most outstanding and distinguishing characteristics of this new variety when grown under normal horticultural practices in Aalsmeer and Boijl, The Netherlands.

1. Abundant purple flowers;
2. Upright plant habit; and
3. A vigorous growth habit.

DESCRIPTION OF THE PHOTOGRAPH

This *Helleborus* plant is illustrated by the accompanying photograph which shows overall plant habit including blooms, buds, and foliage of the plant; the colors shown are as true as can be reasonably obtained by conventional photo-

2

graphic procedures. The photograph is of a whole plant about one-year-old, grown indoors in a glass covered greenhouse in Boijl, The Netherlands and Aalsmeer, The Netherlands.

5 DESCRIPTION OF THE NEW VARIETY

The following detailed description sets forth the distinctive characteristics of 'ABCRD02'. The data which define these characteristics were collected from asexual reproductions 10 carried out in Aalsmeer and Boijl, The Netherlands. The plant history was taken on one-year-old plants grown indoors. Color readings were taken under artificial light. Color references are primarily to The R.H.S. Color Chart of The Royal Horticultural Society of London (R.H.S.) (2005).

15 DETAILED BOTANICAL DESCRIPTION

Classification:

Family.—Ranunculaceae.

Genus and species.—*Helleborus*×*hybridus*.

Common name.—Christmas Rose.

Variety name.—'ABCRD02'.

Plant:

Plant and growth habit.—Upright and vigorous.

Propagation.—In vitro propagation by tissue culture.

Height.—25.0 cm to 35.0 cm.

Width.—25.0 cm.

Time to initiate roots.—6 weeks.

Time to produce a rooted cutting.—Approximately 3 months.

Time to produce a finished plant.—3 months.

25 Stems:

Shape.—Round.

Length.—3.0 cm.

Diameter.—2.0 cm.

Internode length.—0.1 cm.

Texture.—Smooth.

Color.—RHS 139A.

30 Leaves:

Type.—Palmately compound.

Arrangement.—Alternate.

Length.—20.0 cm to 25.0 cm.

40

<i>Width</i> .—15.0 cm to 20.0 cm.	<i>Peduncle</i> :
<i>Shape</i> .—Ovate to lanceolate.	<i>Shape</i> .—Round.
<i>Apex</i> .—Obtuse.	<i>Length</i> .—15.0 cm.
<i>Base</i> .—Lanceolate.	<i>Width</i> .—0.5 cm.
<i>Margin</i> .—Serrate.	<i>Texture</i> .—Smooth.
<i>Texture (both upper and lower surfaces)</i> .—Smooth.	<i>Color</i> .—RHS 187B.
<i>Color</i> .—Immature leaf: Upper surface: RHS 139A.	<i>Pedicel</i> :
